UNITED STATES PATENT OFFICE.

ANDREW L. RIKER, OF FAIRFIELD, CONNECTICUT.

VENTILATOR.

Application filed September 28, 1922. Serial No. 591,078.

To all whom it may concern:

Be it known that ANDREW L. RIKER, a citizen of the United States, and resident of Fairfield, in the county of Fairfield and State of Connecticut, has invented certain new and useful Improvements in Ventilators, of which the following is a specification.

This invention relates to a ventilator, useful for many purposes, but more especially adapted for use as a closure for transoms, doorways, windows, panels, or the like.

An object of the invention is to provide a ventilator which will be a novel, improved and compact article of manufacture, capable of insertion for use with a minimum of effort by unskilled workmen, without danger of destroying the advantageous features for which the ventilator has been devised.

20 A further object is to provide an article of manufacture of the present character which will be simple, durable, efficient and reliable, and which can be inexpensively manufactured, all of the larger elements of the ventilator desirably consisting of sheet metal.

A still further object is to provide a ventilator consisting of a frame having a plurality of spaced apart louvers some of which are fixed and some of which are pivoted to turn on their axes to be swung in one direction to completely close the space within the frame and to be swung in opposite direction to procure passage ways between the respective louvers without opening a direct line of vision through the frame.

Another object is to equip the ventilator with dependable operating mechanism for manipulating the pivoted louvers on their pivots to open and closed positions, the operating mechanism including a practical arrangement limiting the degree to which the louvers can be turned on their pivots.

Yet another object is to provide an article of the kind mentioned having fixed and pivoted louvers so constructed and mounted that passage ways of the maximum dimensions possible may exist between the respective louvers when the pivoted louvers are swung to open position, the pivoted louvers when swung to closed position cooperating with the fixed louvers adjacent them to positively close all of the spaces within the frame. In the accomplishment of the pres-

ent object I preferably utilize L-shaped 55 louvers and I mount the louvers in spaced apart frame members, every other louver being fixedly mounted and the louvers between the fixed louvers being pivotally mounted. 60

Still further objects are to so mount the pivoted louvers that they can be manipulated with a minimum of effort and will, at the same time, dependably remain in open or closed adjusted positions; to so construct 65 and arrange each fixed and each pivoted louver that there will be no interference by the fixed louvers with the manipulation of the pivoted louvers to completely closed position or to wide open position to procure 70 passage ways of maximum dimension; and to provide a ventilator structure, consisting of louvers and oppositely positioned frame members by which the louvers are supported, which can be readily incorporated 75 in a transom, doorway, window, panel, or the like; in such manner that there will be no lines of vision at the locations where the louvers make connection with the frame members or between the outermost louvers 80 of the louver structure and adjacent frame members comprising part of the ventilator itself or part of the building or other construction in which the ventilator is incorporated, all as will be clearly set forth. 85

With the above objects in view, as well as others which will appear as the specification proceeds, the invention comprises the construction, arrangement and combination of parts as now to be fully described and as hereinafter to be specifically claimed, it being understood that the disclosure herein is merely illustrative of the principles and meant to in no way limit the spirit of the invention, changes in details of construction 95 and arrangement of parts being permissible so long as within the scope of the appended claims.

In the accompanying drawing forming a part of this specification,

Fig. 1 is an elevational view of the novel ventilator as when incorporated in a transom, doorway, window, panel, or the like, showing the pivoted louvers in open position;

Fig. 2 is an enlarged longitudinal sectional view of the ventilator showing the pivoted louvers in open position;

Fig. 3 is a view corresponding with the showing of Fig. 2, but disclosing the louvers in closed position;

Fig. 4 is an enlarged vertical sectional view as on line 4-4 in Fig. 2;

Figs. 5 and 6 are enlarged vertical sectional views each showing a fragment of a pivoted louver and spaced apart frame members upon which the louver is mounted, as on line 6-6 in Fig. 2;

Fig. 7 is an enlarged sectional view of one end portion of the ventilator corresponding with the showing of Fig. 2, detailing the mechanism for operating the pivoted louvers;

Fig. 8 is an enlarged sectional view detailing the manner in which the frame members may be connected; and

Fig. 9 shows a fragment of a ventilator having a variant form of frame member incorporated, in accordance with the principles of the invention, in a transom, doorway, window, panel, or the like.

The ventilator consists of a frame of rectangular configuration, louvers fixed in the frame, louvers pivoted in the frame, and arranged between the fixed louvers, all of the louvers being spaced apart, and mechanism for swinging the pivoted louvers on their pivots to open and close the spaces within the frame and between the louvers.

The frame may be composed of sheet metal, and may consist of oppositely disposed members denoted 10, 11 and 12, 13, respectively. All of the members of the frame may be plates having flanges upon their opposite edges, as in Figs. 1 to 8, the flanges of the members 10 and 11 being denoted 14 and 15, respectively, and the flanges of the members 12 and 13 being denoted 16 and 17, respectively.

A manner in which the members 10, 11, 12 and 13 may be joined is best shown in Fig. 8, where in an end portion of a member, say 12, and its flanges 16 are drawn or offset inwardly as denoted at 18, and the flanges, say 14, of the member 10 fit snugly over the drawn in or offset portions 18 to align with the flanges 16. The connection between the members 10 and 12 may be made by means of a rivet 19 passing through said flanges 14 and drawn in or offset portions 18, a bushing 20, extending between the drawn in or offset portions and through which the rivet extends, serving to allow the rivet to clamp the portions 18 and flanges 14 against each other. By the provision of elongated slots (not shown) in the drawn in or offset portions or in the flanges themselves, the members can be slightly adjustable with respect to each other, as will be understood. For convenience, I have in the drawing designated all of the drawn in or offset portions 18, all of the rivets 19, and all of the bushings 20, the connections be-

tween all of the plates desirably being made in the same manner.

The flanges and their drawn in or offset portions are preferably perpendicular to the members 10, 11, 12 and 13, respectively, and all of the flanges extend inwardly of the frame. The ends of certain of the frame members are desirably contiguous with or closely adjacent to the bodies of other frame members. See Fig. 8. 75

The louvers are preferably composed of sheet metal. As shown, they are mounted in the frame to be perpendicular to the members 10 and 11 and parallel with the members 12 and 13, and all of the louvers are of L-shape, although they could be of different construction. 80

Certain of the louvers, denoted 21, have their opposite ends fixed in the members 10 and 11, respectively, each fixed louver having an ear 22 upon its arm 23 secured to the member 10 and an ear 24 upon its arm 25 secured to the member 11, all of the ears 22 preferably extending in the same direction at right-angles from the arms 23, and all of the ears 24 preferably extending in the same direction at right-angles from the arms 25. Numeral 49 designates rivets securing the ears 22 and 24 to the members 10 and 11, respectively. 95

Between each fixed louver is a pivoted louver, denoted 26, having an ear 27 upon its arm 28 pivoted upon the member 10, and an ear 29 upon this same arm pivoted upon the member 11, the arm 30 of each louver 26 being free of ears. The ears 27 and 29 preferably extend at right-angles in the same direction from the arms 28 of the louvers 26, and as shown are situated within the space between the arms 28 and 30. 105

The pivoted louvers are mounted in the members 10 and 11 in the manner best shown in Figs. 2, 3, 5, and 6. That is to say, each of the ears 27 is provided with a hole rotatably receiving a drawn portion 31 of the metal of the member or plate 10 of the frame, and each of the ears 29 is drawn as at 32 to rotatably enter an annular flange 33 consisting of upwardly drawn metal of the member or plate 11 of the frame, the pivotal points for the louvers being arranged adjacent the opposite ends of the arms 28 thereof preferably close to the midwidths of said arms. 110

The ears 29 extend beyond the pivotal points of the arms 28 upon the member 11. 34 denotes an operating bar for manipulating the pivoted louvers. The operating bar is arranged beneath the extensions of the ears 29 to slide upon the plate 11 of the frame and each of the ears has metal drawn therefrom and rotatably entering holes 35 at uniform distances apart in the operating bar. 125

The mechanism for moving the operating 130

bar longitudinally to turn the pivoted louvers on their pivots in a manner which will be obvious, consists of a spindle 36 mounted in the flanges or their drawn in or offset portions adjacent a corner of the ventilator and having a crank 37 and a manipulating handle 38. Near one of its ends the operating bar is bent to general U-shape as denoted at 39 to receive the crank, and the position of that end of the bar, denoted 40, beyond the spindle may be insured by a bushing 20, already described, situated directly above and close to the operating bar.

The metal of the flanges may be drawn as denoted at 41 to provide a dependable bearing for the spindle 36, and the U-shaped part of the operating bar is preferably arranged about the crank so that the slight forward and rearward movements of the operating bar when moved longitudinally to adjust the louvers impart slight endwise movements to the spindle. Evidently, the operating bar will thus insure the spindle against displacement. The spindle has a reduced end 42 mounted in a bearing 41 whereby the larger diameter of the spindle can limit rearward movement of the same. Forward movement of the spindle is checked by engagement of the operating bar with the front flange of the member 11. Obviously, the position of the spindle in its bearings is thus insured.

As shown, the end or outermost louvers are preferably fixed ones, and each has at least one portion extending toward a frame member 12, 13 situated directly between the flanges of said frame member. That is, the free edges of the arms of the louver 43 extend toward the frame member 12 to be situated directly between the flanges 16 preferably against each flange, while the connected edges of the arms of the end or outermost louver 44 extend toward the frame member 13 to be situated directly between the flanges 17 preferably against the face of the frame member 13.

The arms 28 and 30, and 23 and 25, of each pivoted and fixed louver, respectively, are desirably of equal dimensions, the arms 28 and 30 being of slightly less width than the arms 23 and 25 in order that no interference will be offered to manipulation of the pivoted louvers to closed or to wide open position. The vertices of all of the louvers are preferably in alignment with each other and parallel with the longitudinal center of each member or plate 12, 13. The louvers are shown spaced at equal distances apart and when in wide open position the arms 23 and 30, and 25 and 28, respectively, are parallel with each other, the arms 23, 30 having the same angular relation with respect to the front of the frame as the arms 25, 28 have with relation to the rear thereof.

As will be most clear from Fig. 2, the dis-

tance between each louver and those adjacent it is just insufficient to allow a direct line of vision through the frame when the pivoted louvers are in wide open position. When the pivoted louvers are in closed position the free edges of the arms 28, 30 engage the arms 25, 23 of the fixed louvers, respectively, as best disclosed in Fig. 3.

The throw of the crank 37 determines the distance the operating bar can move longitudinally, and hence limits the degree to which the pivoted louvers can be turned on their pivots.

In assembling the louvers with the frame members 10, 11, I desirably utilize rivets 45 as suggested in Fig. 5 to first secure the ears 22, 27 to the frame member 10. I then associate ears 24, 29 with the frame member 11 in the manner already set forth and I may utilize rivets 46 as suggested in Figs. 6, 85 to insure the relative positions of the ears 24, 29 and the frame member 11.

By drawing the metal of the frame member 11 upwardly to form the annular flanges 33, I provide a space 47 between ears 29 and the frame member 11 to afford clearance for the longitudinal sliding movements of the operating bar upon the frame member 11. This will be most clear from Fig. 6. As denoted at 48 in Fig. 4, the ends of the arms 23 of the fixed louvers adjacent the frame member 11 are cut away to offer no interference to manipulation of the operating bar.

The ventilator as illustrated and described is of very simple construction. The frame consists of but four sheet metal plates rigidly secured to each other. The louvers each consist of a single piece of sheet metal bent to L-shape and mounted in the frame. The operating mechanism consists of an operating bar and crank with manipulating handle. The elements going to make the ventilator are relatively few and the positions of all of the elements are positively insured, no liability whatsoever existing that any element can become dislocated or impaired. Hence, the ventilator is durable, reliable and efficient for a long period of time. The provision of L-shaped louvers, some fixed and some pivoted, and their arrangement in the frame in the manner fully set forth, procures passage ways of the maximum dimensions possible between the louvers when the pivoted louvers are in wide open position, and yet, when the pivoted louvers are in closed position, all of the spaces within the frame are effectively closed. In the instance of each ventilator one less than half of the louvers need be manipulated to adjust the louvers.

To incorporate the ventilator in its position of use all that is necessary is to fit the frame into a transom, doorway, window, panel, or the like, denoted A, the flanges of

the frame members 10, 11, 12 and 13 serving the purpose of inclosing the ends of all of the louvers and interlapping with the outermost louvers in a manner to preserve 5 the advantageous features of the ventilator.

In Fig. 9 I have shown a fragment of a ventilator having a variant form of frame member incorporated in a transom, doorway, window, panel, or the like, denoted A'. 19 As disclosed, 10' denotes a frame member of any construction different from that of frame members 10, 11, 12 and 13 secured to the fixture 50 of the transom or the like A', as by means of screws 51, 52 representing 25 a fixed or a pivoted louver attached to the frame member 10' in any convenient manner. 53 represents panels attached to opposite surfaces of the fixture 50 and having their end portions 54 protruding beyond the fixture 50 to envelope the ends of the louvers 52 after the fashion of the flanges of the members 10 and 11. Obviously, panels 53 with protruding portions 54 (not shown) may be utilized to interlap the outermost 25 louvers after the fashion of the flanges of the members 12 and 13. The modified form of ventilator can be incorporated in a transom, doorway, window, panel, or the like, just as readily as the form of ventilator of 30 Figs. 1 to 8, so that no line of vision through the ventilator will be present either at the locations where the louvers make connection with the frame members or between the outermost louvers and the adjacent frame 35 members, it being immaterial whether the protecting flanges constitute part of the ventilator itself or part of the building or other construction in which the ventilator is incorporated.

40 Having thus fully described the invention, what I claim as new and desire to secure by Letters Patent is:

1. A device of the character described, 45 comprising a frame including spaced apart members, L-shaped louvers having their opposite ends fixed in the members, L-shaped louvers between the fixed louvers and having their opposite ends pivoted in the members, all of the louvers being spaced apart, and means for swinging the pivoted louvers 50 on their pivots to open position to allow passages through the frame and between all of the louvers or to closed position to interrupt all of said passages, said means including an operating bar pivotally associated 55 with said pivoted louvers and resting upon and slidable upon one of said members.

2. A device as specified in claim 1, wherein 60 all of the louvers are spaced apart a distance just insufficient to allow a direct line of vision through the frame when the pivoted louvers are in wide open position, and the pivoted louvers are of smaller dimension than the fixed louvers.

65 3. A device of the character described,

comprising a frame constituted by joined plates, each plate having flanges at the opposite edges thereof and extending inwardly of the frame, louvers having their opposite ends fixed in certain of the plates, louvers 70 between the fixed louvers and having integral ears pivoted in the same plates, all of the louvers being spaced apart, and means for swinging the pivoted louvers on their pivots to open position to allow passages 75 through the frame and between all of the louvers or to closed position to interrupt all of said passages, said means including an operating bar pivotally associated with said integral ears of the pivoted louvers and slidable on one of the said plates between its flanges.

4. The combination as specified in claim 3, wherein the fixed louvers are constructed to offer no interference to manipulation of 85 the operating bar.

5. A device of the character described, comprising a rectangular frame consisting of joined plates, louvers having their opposite ends fixed to certain of said plates, 90 louvers having their opposite ends provided with integral ears pivoted to said mentioned plates, each pivoted louver being situated between two fixed louvers, and an operating bar for manipulating the pivoted louvers, 95 said operating bar being slidable on one of said plates and pivotally associated with the integral ear of each pivoted louver, and the fixed louvers being constructed to offer no interference to manipulation of the operating bar. 100

6. A device of the character described, comprising a rectangular frame consisting of metallic plates having flanges, metallic louvers having ears upon their opposite ends 105 fixed to certain of said plates, metallic louvers having ears upon their opposite ends pivoted to said mentioned plates, each pivoted louver being situated between two fixed louvers, and an operating bar for manipulating the pivoted louvers, said operating bar being slidable on one of said metallic plates and pivotally associated with an ear of each pivoted louver, the operating bar being arranged adjacent an end of each fixed and 110 pivoted louver and the fixed louvers offering no interference to manipulation of the operating bar. 115

7. A device as specified in claim 6, wherein the outermost louvers are fixed and have 120 portions interlapping with the flanges of the metallic plates of the frame.

8. A device of the character described, comprising a rectangular frame consisting of metallic plates having flanges, metallic 125 L-shaped louvers having integral ears upon their opposite ends fixed to certain of said plates, metallic L-shaped louvers having integral ears upon their opposite ends pivoted to said mentioned plates, each pivoted louver 130

being situated between two fixed louvers, an operating bar for manipulating the pivoted louvers, said operating bar being slidable on one of said metallic plates and pivotally associated with an integral ear of each pivoted louver, and a spindle with crank and operating handle for manipulating said pivoted louvers on their pivots, the operating bar being arranged adjacent an end of each fixed and pivoted louver and the fixed louvers having cut-away portions to offer no inter-

ference to manipulation of the operating bar.

9. A device as specified in claim 8, where-
in the outermost louvers are fixed and have 15
portions interlapping with the flanges of the
metallic plates of the frame.

Signed at Bridgeport, in the county of
Fairfield and State of Connecticut, this 26th
day of September, A. D. 1922.

ANDREW L. RIKER.
